UNITED STATES PATENT OFFICE

2,631,502

VERTICAL ROTARY TOOL SUPPORT

Richard Ford Hall, Binghamton, N. Y.

Application March 11, 1949, Serial No. 80,995

1 Claim. (Cl. 90—58)

1

The present invention relates to a vertical rotary tool support and it consists in the combinations, constructions and arrangements of parts herein described and claimed.

Generally there is provided a rotary work support which extends in a vertical plane and which is provided with novel means for moving the same to selected positions together with novel means for taking up "play" in the moving parts of the mechanism. Novel means is also supplied for keeping the apparatus dust free.

It is accordingly an object of the invention to provide an apparatus of the character set forth which is simple in its construction and operation and yet effective and efficient in use.

Another object of the invention is the provision, in a device of the character set forth, of novel means and mechanism for taking up "play."

Another object of the invention is the provision of novel means for moving a worm wheel which forms a part of the apparatus.

A further object of the invention is the provision of a device of the character set forth in which friction within the same is reduced to a minimum.

Other and further objects of the invention will become apparent from a reading of the following specification taken in conjunction with the drawings, in which:

Figure 1 is a side elevational view of an embodiment of the invention.

Figure 2 is a fragmentary sectional view taken along line 2—2 of Figure 1.

Figure 3 is a plan view of the device shown in Figure 1.

Figure 4 is a sectional view taken substantially along line 4—4 of Figure 1.

Figure 5 is a sectional view taken substantially along line 5—5 of Figure 1.

Figure 6 is a reduced end elevational view of the device shown in Figure 1.

Figure 7 is a fragmentary perspective view of the locator for adjusting the shaft.

Figure 8 is a sectional view taken along line 8—8 of Figure 3, and

Figure 9 is a plan view of the locator in assembled position with the shaft.

Referring more particularly to the drawings, there is shown therein a vertical rotary tool support comprising a base 10 which is provided with an upwardly extending vertically disposed, integrally formed plate 11 which is provided with a rather large opening 12 in one side thereof.

A horizontally extending opening 13 extends

through the plate 11 and communicates with the opening 12 and a hollow bolt 14 is disposed in the opening 13 and an opening 15 extends through the bolt 14 which is provided with a hollow head

16 at one end and is threadably connected with a work support 17 at its other end as indicated at 18. An opening 18' is formed in the work support and registers with the opening 15 in the bolt 14.

10 A relatively small thrust bearing 19 surrounds the bolt 14 and is mounted in a recess 20 in one side of the plate 11 and is retained therein by means of the bolt head 16. A relatively large thrust bearing 21 is mounted in a recess 22 upon the face of the support 17 and in a recess 23 formed in the plate 11 on that side thereof opposed to that containing the recess 20.

20 A worm wheel 24 is located in the opening 12, is revolvably mounted upon the bolt 14 and is affixed to the work support 17 by means of screws 25.

25 The upper end of the plate 11 is provided with a horizontally extending opening 26 in which is disposed a shaft 27 to the inner end of which is affixed by means of a key 28 a worm 29 which extends downwardly through an opening 30 to enmesh with the worm wheels 24. The outer end of the shaft 27 is provided with an operating handle 31 which is held thereon by a retaining nut 32. A pointer 33 is affixed to the top side 30 of the plate 11 by means of a screw 34 and is adapted to coact with a dial 35 which is mounted upon the shaft 27 by a slip fit. A lock nut 35a is threadably mounted on the shaft 27 outwardly of the dial 35.

35 A locator member 36 is provided with a centrally disposed opening 37 through which the shaft 27 extends and the member 36 is provided with upper and lower rounded faces 38 and 39, respectively, and which fit snugly in rounded recesses 40 and 41, respectively, formed in the plate 11. One end of the member 36 extends through an opening 42 formed in one side of the plate 11 to a point flush with the surface thereof and to this end of the member 36 there is affixed by means of screws 43 a dependent plate

44 having an arcuate slot 45 in its lower end through which extends a locking screw 46 which is threaded into the plate 11.

40 Thrust bearings 47 and 48 are provided upon either side of the member 36. The bearing 47 is provided with an adjusting nut 49 which is threadably mounted upon the shaft 27 and the bearing 48 abuts the inner end of the worm 29.

45 A felt dirt sealing ring 50 is interposed between

the plate 11 and the inner face of the work support 17. A cap 51 encloses the bolt head 16 and the bearing 19 and is affixed to the plate 11 by means of screws 52. To lock the table 17 in any selected position, a lock nut 53 is threaded through the plate 11 and is adapted to bear against the worm wheel 24. A plug 54 provides access to the opening 26. An opening 51a is provided in the cap 51 in registry with the openings 15 and 18'.

The table 17 is provided with calibrated indicia 17a on its outer face and a pointer 60 is affixed to the plate 11 by means of a screw 61. In the face of the work table 17 there is provided a pair of T-slots 62 in each of which is a work bolt 63.

In operation, it will be apparent that when it is desired to move the support or table 17, it is only necessary to move the handle 31 thereby rotating the shaft 27 and consequently the worm 29. This, in turn, will cause the rotation of the worm wheel 24 upon the bolt 14 and thus cause rotation of the table 17. In order to eliminate any possible play between the worm and the worm wheel, the nut 46 may be loosened and the arm 44 moved in a clockwise position as viewed in Figure 1, thus causing the shaft 27 and the worm 29 to move into closer contact with the worm wheel 24. When the worm 29 and the worm wheel 24 have been brought into proper relationship, the nut 46 may again be tightened. Since the dial 35 has calibrations thereon, the same may be read by means of the pointer 33 and thus a fine calculated adjustment may be made at will. With construction above set forth it is possible to move the table 17 by means of the handle 31 with a minimum of friction thus permitting the operator of the apparatus to "feel" the action of tools upon the work and thus allowing him to perform a much better job at all times, the indicia 17a and the pointer 60 assisting greatly in this respect.

While but one form of the invention has been

shown and described herein, it will be readily apparent to those skilled in the art that many minor modifications may be made without departing from the spirit of the invention or the scope of the appended claim.

What is claimed is:

In a device of the character described including a base and a vertically extending plate, a vertically extending work table revolvably mounted in the outer face of said plate, a worm wheel affixed to the rear of said work table, a shaft extending substantially horizontally through said plate, a worm gear affixed to said shaft and enmeshed with said worm wheel, and an operating handle for said shaft, the provision of means for adjusting the shaft and worm with respect to the worm wheel, said means including an adjusting block revolvably mounted in said plate and having an axis of revolution perpendicular to the longitudinal axis of said shaft, said block having an opening therethrough for the revoluble reception of said shaft therein, an arm affixed to the outer face of said block and having an arcuate slot formed adjacent its outer end, and a headed screw extending through said slot and threadably engaged in said plate.

RICHARD FORD HALL.
